UNITED STATES PATENT OFFICE.

JOSEPH V. ROMIG, OF ALLENTOWN, PENNSYLVANIA, ASSIGNOR TO BROWN & SHARPE MANUFACTURING COMPANY, OF PROVIDENCE, RHODE ISLAND.

CLEARANCE GAUGE.

Application filed October 17, 1923. Serial No. 669,169.

To all whom it may concern:

Be it known that I, JOSEPH V. ROMIG, a citizen of the United States, residing at Allentown, in the county of Lehigh and 5 State of Pennsylvania, have invented new and useful Improvements in a Clearance Gauge, of which the following is a specification.

This invention relates to certain new and 10 useful improvements in a clearance gauge and more especially in a gauge for measuring the clearance of the teeth of milling cutters and the like.

The object of the invention is to provide 15 a simplified and practical tool of this character which may be economically produced thereby permitting a low sales cost so that every operator of milling cutter grinders may easily equip himself with a gauge.

20 The invention resides in a protractor device slidably and frictionally mounted on a bar for being moved therealong against a cutter tooth, the protractor device being itself adjustable for determining the angle 25 of clearance.

The invention will also be found to reside 30 in the salient features of construction and the arrangements and combinations of parts hereinafter described and claimed, reference being made to the accompanying drawings wherein:—

Figure 1 is a side elevation of the improved gauge embodying the present invention;

35 Figure 2 is a fragmentary view depicting the slide in lengthwise section;

Figure 3 is a transverse sectional view on line 3—3 of Figure 1;

Figure 4 illustrates the manner of using 40 the improved gauge;

Figure 5 is a longitudinal edge view of the gauge; and Figure 6 is a transverse section on line 6—6 of Fig. 4.

45 Referring more in detail to the accompanying drawings, the numeral 1 designates a bar-like body having one end formed into a laterally enlarged head 2 whose outer edge is cut out, as at 3, to form a seat to receive the arbor of the cutter to be operated on.

50 The seat 3, has two inwardly converging side walls which meet at a point in alignment with the adjacent side edge of the body 1, as is clearly seen in Figures 1 and 4.

Thus, the edge of the body will be brought into radial alinement with the arbor, and the 55 cutter thereon.

A slide 4 is mounted on the body and is frictionally held in adjusted position thereon by an inclosed leaf spring 5 interposed between the lower edge of the body and the 60 opposing edge wall of the slide which latter wall is centrally depressed to receive an elbow bend of the spring, as indicated at 6, to secure the spring against accidental displacement. The opposite edges of the slide 65 are serrated or roughened, at 7 to facilitate adjusting the slide with the fingers. One side of the slide has a forwardly extending ear 8 and a rearwardly extending dial 9 provided with graduations depressed in its 70 face.

A clearance measuring device is pivoted at 10 on the ear 8 and has a stop 11 and an angular blade 12 on one side defining a tooth-receiving recess, and a needle arm or 75 finger 13 extending from the pivot to operate over the dial, the extreme end being curved to resiliently engage or click into the graduations to hold the blade 12 in a set 80 position, as shown in Fig. 5.

In operation, after the cutter 15 has been placed in the grinding machine on the arbor or mandrel 14, and a trial pass made over one tooth 16 by the grinding wheel, the tooth is then rotated around to the vertical position, as indicated in Figure 4. The gauge is then set with its head 2 seated on the arbor, as in Figures 1 and 4, and the slide 4 moved down to bring the notch or stop 11 over and into engagement with the tooth. 90 The blade 12, in zero or normal position, is tangent to the cutter 15 and in order to bring the blade into flat engagement with the peripheral edge 17 of the tooth to measure its clearance, the point of arm 13 is moved over the dial from which the angle of clearance may be easily read from the dial in degrees from the tangent. The clearance angle is then checked to the accurately checked protractor and, if incorrect, the finger or arm is elevated or lowered to the correct position.

100 In this manner the correctness of the angle is checked on the very first tooth ground. As the blade 12 at zero position 105 is tangent to the cutter, the readings on the

dial will be in degrees of angularity to the tangent point.

The tool has been designed in its simplest and most useful form enabling every grinder 5 hand or user to have one because of its low cost of manufacture. The protractor is accurately set by reason of the finger point clicking into the dial graduations.

The frictional spring mounting of the 10 slide permits an easy sliding action without play and eliminating the use of a set screw. The head 2 is so shaped to squarely seat on the mandrel of various sizes, as indicated in Figure 1.

15 Having thus described my invention, what I claim as new and desire to secure by Letters Patent is:—

1. A clearance gauge comprising a bar, a slide thereon, a clearance measuring device pivoted on the slide and having a tooth-receiving recess spaced from the pivotal mounting for receiving the cutting edge of the tooth to be gauged, the recess of said device having one wall forming a stop to 20 be abutted by the tooth and another wall 25 for engaging the clearance face of the tooth,

and means for indicating the degree of clearance.

2. A clearance gauge comprising a bar, a slide thereon, and a clearance gauge device 30 pivoted on the slide and formed with a tooth-receiving recess having one wall constituting an angular clearance blade extending therefrom and an adjacent wall constituting a stop. 35

3. A clearance gauge comprising a support, a slide thereon, a dial on the slide having depressed graduations, and a clearance measuring device supported on the slide for movement, said device having a pointer 40 operating over the dial and interlocking with the graduations thereof.

4. In a clearance gauge, a support, a clearance measuring device movably mounted on the support and having a tooth-receiving notch one wall of which constitutes a clearance blade leading therefrom, and means for determining or indicating the degrees of clearance. 45

In testimony whereof I have signed my 50 name to this specification.

JOSEPH V. ROMIG.
